UNITED STATES PATENT OFFICE

DORSEY M. WIRTH, OF BUCYRUS, OHIO

BELT BUCKLE

Application filed July 7, 1930. Serial No. 466,245.

This invention relates to expanding buckles such as belt buckles in which a yielding resilient spring member is incorporated so as to be interposed between one end of the belt and the buckle body whereby the girth of the belt is automatically and continuously accommodated to the movements of the wearer thereof thereby promoting his comfort in an obvious manner without in any way sacrificing the garment supporting qualities of the belt.

It is the object of this invention to provide a buckle of this type which may be conveniently and quickly associated with a belt of any conventional type or with any strap or other like securing or suspending means.

These and other objects of the invention, its nature, and arrangement and combination of parts will be readily understood by any one acquainted with the art to which this invention relates upon reading the following description of the drawings in which:

Figure 1 is a back view of the preferred embodiment of my invention disclosing the manner of attachment to a belt.

Figure 2 is a longitudinal sectional view taken on the line 2-2 of Figure 1.

Figure 3 is a perspective view of one form of one of the parts of the belt connector assembly referred to herein as the yoke.

Figure 4 is a perspective view of a preferred form of one of the parts of the belt connector assembly referred to herein as the belt connector-loop.

Figure 5 is a back view similar to Figure 1 of another embodiment of my invention.

Figures 6 and 8 are further modifications.

Figure 7 is a form of link and jaw carrier employed in the form of the invention illustrated in Figure 6.

Figure 9 is a perspective view of one form of a combined yoke and belt engaging jaw such as is employed in the embodiment of the invention illustrated in Figure 8.

Referring in detail to the drawings it will be observed that all the illustrated forms of my invention have in common a buckle body designated either 12, or 12a, 12b and 12c, and a belt connector assembly consisting of the closed loop 5 carrying on its legs the coiled

spring 6, and the yoke designated 10, or 10a, or 19, which connector assembly is pivotally connected to the buckle body in each form. Of course, the specific differences will be evident as the description of each form is herein set out.

Referring to the form of my invention in Figure 1 it will be seen that the numeral 12c designates a buckle body of suitable form such as generally rectangular having inwardly directed ears constituting journal mountings. In this figure the belt connector assembly consists of the jaw carrying link 22, the yoke 10a being pivoted at its ends at 16a to the arms 22a of the link, the link in turn having pivots 23 journaled in the above mentioned journal mountings of the buckle body. The closed loop 5 carries on its legs the compression spring 6. The belt end is passed through the closed loop or fastened to one end thereof in any suitable manner, and the loop, being slidable in the bight portion of the yoke in holes 11, and the loop being movable against the pressure of the spring 6, the belt is yieldingly and resiliently connected to the buckle body. The link 22 carries on its under face a belt engaging jaw 24 similar to that shown at 20 in Figure 9 whereby the free end of the associated belt is adjustably retained by clamping it between the jaw and the underside of the buckle body. The link 22 consists of the generally rectangular body portion 22b from one longitudinal side of which extend angularly and oppositely a pair of arms having the terminals 22a forming journals for pins 16a which pivotally connect the ends of the legs of the yoke 10a thereto. The yoke, as evident in the drawings, consists of a bar preferably right angularly bent into the form of a U provided with a pair of holes 11 in its bight portion for slidably accommodating the legs of the closed loop 5 as explained above. The closed loop 5 may be a bar or wire bent into the form of a U in which the bight portion is semi-circular, and has the free ends of the legs directed outwardly and then inwardly to form the bends designated 9 and straightened to come into end to end abutting relation at right

angles to the sides or legs. The permanent 5
ly attachable belt end is secured upon the portion
of the loop remote from the semi-circular
bight portion and the belt and loop are prefer-
ably so proportioned that the side edges of
the belt may extend over and be retained by
the bends 9. As above stated, the legs of the
loop 5 slide in holes 11 in the bight portion of
the yoke, and a helical spring 6 circumscribed
10 on the legs and bight portion of the closed
loop has its ends abutted against the in-
ward side of the bight portion of the yoke so
that movement of the loop in the direction of
pull of the belt is yieldingly resisted by the
15 spring and the loop is retracted whenever the
pull on the belt is not being exerted.

Referring to Figure 5 a modification of the
structure of Figure 1 is illustrated. Comparison
20 of Figures 5 and 1 will disclose that
the forms of Figures 5 and 1 differ only in
the fact the ends of the yoke 10 in Figure 5
are pivoted to the buckle body 12 through the
agency of a bar 14, the ends of which extend
25 outwardly beyond the yoke ends to function
as pivots journaled in the ears of the buckle
body. Mounted on the bar 14 is a belt gripping
jaw similar to that designated 20 and 24.

The form illustrated in Figure 8 differs
30 from the form illustrated in Figure 5 only by
the construction of the yoke and method of
mounting the belt gripping jaw. In the
form of Figure 8, there is formed in one piece
35 of relatively heavy material the yoke proper
and the jaw 20 as particularly clearly shown
in Figure 9. The ends of the jaw portion 20
are provided with the pivots 21 for journal-
ing in the buckle body.

The form of the invention shown in Figure
40 6 is very similar to that shown in Figure
1. In fact, the only distinguishing difference
of Figure 6 is in the structure of its link
and its jaw member. The link and jaw of
45 Figure 1 are preferably an integral casting
whereas the link and jaw of Figure 6 may be
adequately formed by stamping or by stamp-
ing and welding or brazing. It is to be under-
stood however, that these recommendations
50 are not made in the sense of limitations
upon any possible method of constructing the
link and jaw structure, and any part or parts
of the invention might be constructed of ma-
terial other than metal. The link of Figure
55 6 consists of a pair of parallel side bars 16
carrying across one pair of ends the bar 14a,
to which ends and which bar a suitable belt
engaging jaw of the general type designated
at 24 in the drawings is mounted. A curvate
60 cross member 18 is rigidly secured to the sides
16. The bar 14a may be placed in position
in holes 17 on the said pair of ends and soldered
or brazed therein so as to form a rigid
association. The jaw may be mounted by
65 similarly soldering, brazing or welding or
may be associated with the link in any way
found desirable and practical. The ends of

the side bars remote from the holes 17 are
slightly angularly bent outwardly and then
returned into parallelism as at 16b. On the
edges of portions 16b and on the same edges
70 to which the cross member or saddle 18 is at-
tached there is formed a pair of oppositely
and inwardly directed lugs 16a which are
adapted to engage in the holes 13 in the ends
75 of the legs of the yoke 10a and function as
pivots.

It is believed that the above descriptions
and the drawings make clear the nature of
my invention and the manner of making and
using the same.

It is to be definitely understood that I do
not desire to limit the application of this in-
vention to the particular modification set
out herein to illustrate the principles there-
of, and changes may be made in material or
80 structure or arrangements of parts consist-
ent with the spirit and scope of the invention.

I claim:

1. A belt buckle of the class described com-
prising a buckle body, and an expanding belt
connector assembly pivotally connected to
said buckle body, said belt connector assem-
bly comprising a yoke, means pivotally con-
necting said yoke to the buckle body, an elon-
gated belt connector slidably carried by the
yoke, a belt connecting portion at one end of
the connector and a spring on the connector
and reacting against the other end of the con-
nector and the bight portion of the yoke for
yieldably resisting opposite relative longi-
tudinal movement of the connector and yoke,
100 and a belt engaging jaw carried by said as-
sembly for cooperating with said buckle body
for adjustably retaining the free end of the
belt.

2. An automatic spring operated belt
buckle comprising a loop adapted to be at-
tached to one end of a belt, a compressible
and expanding spring on said loop, a U-
shaped yoke having its bight portion mount-
ed on said loop and engaging said spring, the
ends of said U-shaped yoke being formed
with holes, a rod disposed transversely of
said U-shaped yoke in said holes and pro-
jecting beyond each side thereof, a buckle
body having flanges pivotally receiving the
projecting ends of said rod, and a belt en-
gaging jaw mounted between said flanges for
co-operating with said body to clamp an end
of the belt.

3. An expanding belt buckle structure com-
prising an elongated loop connected at one
end to an end of a belt, a spiral compression
spring on said loop, a U-shaped yoke having
holes in its bight to receive the side members
of said loop, said U-shaped yoke adapted to
slide on said side members of the loop against
the resistance of said spring, the ends of said
U-shaped yoke being provided with holes, a
buckle body, a connecting link pivoted be-
tween the free ends of said U-shaped yoke and
130

said buckle body comprising a pair of parallel legs having at one end inwardly turned hooks to engage pivotally in the holes on the ends of the U-shaped yoke and at the other 5 ends holes, a bar in said holes having its ends extending beyond the sides of the legs journaled in said buckle body, a saddle portion connecting and spacing said parallel legs, and a belt engaging jaw mounted to cooperate 10 with the buckle body to clamp an end of the belt.

4. A belt buckle of the class described comprising an elongated loop adapted to be connected at one end to a belt, a compression 15 spring of spiral form disposed on said loop, a yoke having holes in one portion thereof to slidably accommodate the sides of said loop and permit said yoke to slide longitudinally on the loop against the resistance of the 20 spring, the yoke including a fixed transverse bar having at one lateral face a belt engaging jaw which has projecting at its ends pivot lugs, and a buckle body receiving said pivot 25 lugs and adapted to cooperate with said belt engaging jaw to hold a portion of the belt.

In testimony whereof I affix my signature.
DORSEY M. WIRTH.
